CONTROL APPARATUS

Eldon D. Raney, Columbus, Ohio, assignor to Raney Co Incorporated, Columbus, Ohio, a corporation of Ohio

Application April 23, 1938, Serial No. 203,887

4 Claims. (Cl. 158—28)

The present invention relates to control systems for oil burning apparatus and more particularly to automatic controls for preventing injection of ignitable fuel into the furnace except when ignition is present and only after a predetermined purging time has elapsed after the previous cessation of injection of fuel.

One of the objects of the present invention is to provide an improved control system for a fuel burning apparatus in which the circuit, utilized for starting the apparatus, is rendered ineffective after such starting and it is not reconditioned to restart the apparatus until a predetermined time has elapsed after the cessation of operation of the apparatus.

Another object of the present invention is to provide an improved control system for a fuel burning apparatus in which the first circuit to be energized, in response to a demand for heat from the apparatus, is the secondary circuit of a transformer, the primary circuit of such transformer being controlled by a time delay device and not being in a condition to be energized until a predetermined time after the previous cessation of operation of the apparatus, the said primary circuit being rendered ineffective, by the delay device, substantially immediately after the starting of the fuel burning apparatus, but, before the primary circuit is deenergized, a second primary circuit is established for maintaining the transformer operative.

Other and further objects and advantages will be apparent from the following description, reference being had to the accompanying drawing wherein preferred forms of embodiments of the present invention are clearly shown.

In the drawing:

Fig. 1 is a diagrammatical view of one embodiment of the invention, and,

Figs. 2 and 3 are fragmentary diagrammatical views, each showing a different embodiment of the invention.

Referring to the drawing the means which controls the flow of fluid is herein shown as a motor 20 which may be utilized for actuating a fuel pump and an air fan of the fuel burning apparatus. The motor 20 is controlled by a switch 21 and the circuit therefor includes high voltage line 22, wire 23, motor 20, wire 25, stationary contacts 26 and 27 of switch 21, which contacts are bridged by an electro magnetically operated contact 28, wire 30, heating coil 31 of time delay device 32, wire 35, stationary contacts 37 and 38 of a safety switch 39, which contacts are bridged

by a movable contact 40, and the other main line 41.

Switch 21 is closed when the electro magnet coil 43 thereof is energized. The circuit for winding 43 includes secondary winding 44 of transformer 45, wire 46, winding 43, wire 48, movable contact 49 of room thermostat 50, contact 51 and wire 53. The safety switch 39 normally is closed, and, when the starting switch 21 is closed by room thermostat 56, current will be supplied to the motor 20. Switch 21 also controls the ignition for the fuel. Any type of ignition may be provided and that herein shown is the high voltage type including primary winding 55 and the secondary high voltage winding 56, the spark gap being indicated at 57. The ignition is connected in parallel with the motor, the parallel circuit including a wire 59 connected with wire 23, stationary contact 60 of ignition switch 61, movable contact 62, wire 63, winding 55 and wire 64, which latter is connected with wire 25.

It will of course be understood that the secondary circuit of the transformer will not be energized unless the primary coil 66 of transformer 45 is energized. The circuit for coil 66 includes line 22, wire 67, winding 66, wire 68, a stationary contact 69 of time delay device 32, a movable bimetallic strip 71 of time delay device 32, which strip is anchored at 72, wire 73, heating coil 31, wire 35, safety switch 39 and line 41. Whenever strip 71 engages contact 69, current is supplied to the transformer whereby the motor can be started upon demand by the room thermostat 50.

If the heating coil 31 is in series only with coil 66 of transformer 45, the heat generated by coil 31 is not sufficient to flex bimetal 71 from contact 69 due to the resistance offered by coil 66. However, when the heating coil 31 is in series with the motor 20, sufficient heat will be generated in coil 31 to cause thermostat 71 to flex away from contact 69 but this flexing will be gradual and will occur after a second transformer circuit is completed. This second transformer circuit includes line 22, wire 67, winding 66, wire 75, contact 22 of starting switch 21, which is now engaging contact 27, wire 30, coil 31, wire 35, safety switch 39 and line 41. Thus it is apparent that energization of primary transformer winding 66 is maintained after thermostatic strip 71 separates from contact 69 and the second transformer primary circuit will be maintained as long as coil 43 of the secondary circuit is energized.

When the coil 43 is deenergized, either by the

room thermostat 50 or power failure of any type, the armature operated contact 28 of starting switch 21 will be separated from contact 26 and 27, to thereby interrupt the circuit to the motor 5 and the second primary transformer circuit including wire 75. Although there is a reoccurring demand for heat by the thermostat, or in the event of reestablishment of a previous cessation of electrical energy, the motor 20 cannot be 10 started until a predetermined time has elapsed after the previous cessation of operation thereof. This is apparent because the first primary circuit for the transformer is interrupted at 71 and 69 and the second transformer circuit is interrupted at 28 and 27. At this time no current is flowing in coil 31 of time delay device 32 and therefore bimetallic strip 71 is cold or is cooling. After a predetermined time, strip 71 will reengage contact 69 to thus reestablish the first primary 15 transformer circuit. The time interval between the cessation of operation of the motor and the recondition, of the first primary circuit of the transformer, by reengagement of strip 71 with contact 69, is sufficient to permit purging of non-spent gasses from the furnace chamber.

In the event that the fuel does not ignite, during starting of the apparatus or in the event of flame failure during the operation of the motor 20, the motor 20 is rendered inoperative by the 20 separation of contact 40, of safety switch 39, from contacts 37 and 38. The safety switch 39 includes a lever 76 pivoted at 77 on a stationary bracket 78. This lever is normally biased to hold the contacts closed by a spring 79 but when 25 the lever 76 is thrown past its dead center position, with respect to the spring 79 and pivot 77, the lever 78 will be biased to open the contacts of the switch, and the lever must be reset manually. The lever 76 is adapted to be actuated 30 by a lever 81 of snap acting mechanism 82. This snap acting mechanism includes a lever 83 and, like lever 81, is pivoted at 84 on the bracket 82. A spring 85 biases the levers 81 and 83 either in 35 one direction or the other. In the present illustration the lever 83 is moved upwardly by a bimetallic strip 87 when the strip is heated. Continuous upward movement of the strip 87 causes the lever to move beyond its dead center position, with respect to the spring 85 and lever 81, 40 whereby lever 81 will be moved upwardly. During normal operation, that is when heat is generated by the fuel burning apparatus, the upward movement of lever 81 is limited by a combustion responsive controller 88. This controller includes a thermostat 89 anchored at 45 90 and is responsive to heat of combustion. The lower part of thermostat 89 is adapted to move to the right when combustion takes place to move a stop 91 in the path of the lever 81. The 50 stop 91 is operated through the usual type of slip clutch. The sidewise movement of the stop 91 is limited by stops 92 and 93, the clutch permitting further movement of the thermostat 89 but causing retractive movement of the stop 91 55 substantially immediately upon change of temperature of thermostat 89. In the event of failure of ignition of the fuel, during starting, the stop 91 will not stop the upward movement of lever 81 and a leg 95 of lever 81 will engage a 60 leg 96 of lever 76 and will lift the lever 76 beyond its dead center position to thereby open the safety switch 39.

The thermostatic strip 87 of the snap acting mechanism 82 is heated by an electric heater 98. 75 The circuit for this heater includes line 22, wire

61, wire 99, coil 98, strip 87, contact 100 carried by lever 83, wire 101, wire 25, contacts 26, 28 and 27, wire 30, heater 31, wire 35, safety switch 39 and line 41. Thus it is apparent that when the starting switch 21 is closed, coil 98 is energized and will, after a predetermined time, operate the snap acting mechanism 82. The time interval from the starting of heating of the coil 98 until the time when the snap mechanism 82 moves upwardly through its dead center position 10 is sufficient for normal starting of the fuel burning apparatus so that in the event of failure of ignition the safety switch will be operated to interrupt the initial circuit of the system.

In the event it is desirable to provide ignition during the starting period only, the ignition circuit may be interrupted, as shown, by the snap mechanism 82, that is the contact 62 of the ignition circuit is carried by the lever 81.

In the embodiment shown in Fig. 1 the contact 100 is separated from thermostatic strip 87 when the lever 83 is toggled upwardly through dead center whereby the circuit to the heating coil is interrupted. The strip 87 then cools and returns to the position shown, while the apparatus is in operation. The lever 83 is returned to the position shown, namely the starting position, when the armature 28 falls out. In the diagrammatical illustration, the armature 28 is shown as carrying a rod 103 which falls by gravity and is assisted by a spring 104. This rod 103 carries a pin 105 arranged to engage the upper side of lever 83 and move the lever 83 downwardly when the armature 28 falls out. The pin 105 will be lifted to its upper position when the armature is attached and may function as a stop for limiting the upward movement of the lever 83. The position of stop 91 of combustion control 88, when in stopping position for lever 81, is such that the lever 81 will also be 40 snapped downwardly when the armature 28 falls out, so that ignition is insured for the succeeding restarting of the system. The downward movements of lever 83 and 81 are limited by a stop 106 and contact 60, respectively.

In the event of flame failure after ignition has taken place, the cooling of the thermostat 89 will cause the stop 91 to move to the right and slide off of the edge of lever 81. The snap acting mechanism 82 being biased upwardly will cause the lever 81 to move further upwardly which in turn will cause leg 95 to engage leg 96 and thereby snap lever 76 to the circuit opening position. The safety switch 39 must be reset manually. Thus it is apparent that the snap acting mechanism for the safety switch is biased at all times after the starting operation toward a safety switch opening position and that the safety switch is prevented from operating only by the combustion control. Therefore, as soon as there is a failure of fuel, the safety switch is open at the instant that the temperature of the thermostat 89 recedes. Thus quick operation of the safety switch is assured.

It is desirable to limit the heating of coil 31 and strip 71 of the time delay device 32. This is accomplished by shunting the current through contact 107 on strip 71, stationary contact 108 and wire 109 connected with wire 35. Thus it will be seen that when contact 107 engages contact 108, the heating coil 31 will be either short circuited or part of the current will be shunted through wire 109. As soon as the coil 31 and strip 71 cools slightly contact 107 will separate from contact 108 to interrupt the shunt. It will 75

of course be understood that at no time will strip 71 be cooled to such a degree as to engage contact 69 except when contact 28 is separated from contacts 26 and 27.

5 The present illustration includes a differential type room thermostat in which the bimetal 111 thereof is pivoted at 112 and the temperature at which the same operates is governed by a hand adjusting cam 113. Upon cooling of the room 10 containing the thermostat, the right arm of thermostatic strip 111 moves to the left and first engages spring contact 49 which is anchored at 114 and then causes contact 49 to engage contact 51 to complete the circuit of the secondary 15 transformer traced above. As the room temperature increases, the right hand arm of strip 111 moves to the right and the contact 49, normally biased to the right, follows the right arm of strip 111. A circuit, however, is maintained through 20 the coil 43 after strip 111 moves far enough to permit contact 49 to separate from contact 51. This circuit includes coil 44, wire 46, winding 43, wire 48, contact 49, strip 111, wire 115 contact 116, which contact is closed on contact 117 when armature 28 is attracted, contact 117 and wires 118 and 53. This holding circuit is maintained as long as the armature 28 is raised and 25 until the room thermostat 50 is heated sufficiently to cause strip 111 to separate from contact 49. The point at which strip 111 separates from 49 is governed by an adjustable screw 120 which in effect provides a control of the differential between the opening and closing 30 of the circuit of the starting switch coil 43.

If desirable the heating coil 98 of the safety switch actuating mechanism may be maintained 35 energized throughout the period when the motor 20 is operative. In that case it can be connected as shown in Fig. 2 wherein wire 101 is directly connected to the coil 98. In this view the snap mechanism 82 is shown in the position which it assumes after it is snap actuated. In this embodiment the bias of spring 104 and the weight 40 of the armature 28 and rod 103 and the other parts carried thereby is sufficient to overcome the bias of not only the spring 85 but also the tension of thermostatic strip 87, when the armature is released by the coil 43. It will be noted 45 that the only function to be performed by the current induced into the secondary winding 44 is to energize coil 43. Therefore, sufficient current is available in coil 43 to lift a relatively heavy 50 armature.

55 It may be desirable to limit the temperature of heating coil 98, in such case the construction may be like that shown in Fig. 3 in which the thermostatic strip 87 is pivotally mounted at 120 and carries a contact 121 which engages the contact 122. The circuit for the heating coil includes the contacts 122 and 121 and the wire 101 is connected to the pivot 120. When the thermostatic strip 87 is heated the arms 124 and 125 tend to spread but the spring 126 under arm 125 restrains the movement of arm 125 sufficiently so 60 that arm 124 moves first and after it snaps the switch mechanism 82 through center, the upward movement of arm 124 is stopped by lever 83. Further movement of the strip 87 will be a downward 65 movement of arm 125. This downward movement will cause a separation of contact 121 from contact 122 to thereby interrupt the circuit to the heating coil. As soon as the heating coil cools 70 slightly, the spring 126 will force contact 121

against contact 122 to again complete the circuit through coil 98.

75 The making and breaking of the heater coil 98 of the snap acting mechanism of the safety switch 39 is made possible by devising a circuit in which the heating coil 98 is connected in parallel with the motor and the primary winding 66 of transformer 45 and the arranging of this parallel circuit so that it is capable of being energized only when the motor is energized.

10 While the forms of embodiments of the present invention as herein disclosed constitutes preferred forms, it is to be understood that other forms might be adopted, all coming within the 15 scope of the claims which follow:

1. A fuel burner control system comprising in combination, a transformer including a primary winding and a secondary winding; a circuit for energizing the primary winding; a thermally actuated time switch in the circuit, said switch being adapted to open the circuit when heated to a predetermined temperature; a second circuit for energizing the primary winding; an electrically operated fuel feeding device, said device having a greater current capacity than said primary winding; a circuit for energizing said device; means energized by the secondary winding for closing said second circuit and the last mentioned circuit; and electric heating means in series with the aforementioned circuits, said heating means being adapted to heat said thermal switch to said predetermined temperature when the fuel feeding device is energized.

2. A fuel burning control system comprising in combination with a source of current, a relay; 35 electrically operated fuel feeding mechanism and a heating element connected in series circuit relation and connected to said source of current by said relay; two circuits for the relay, one of said circuits being closed by the relay; a device 40 actuated by the heating element for opening the other of said relay circuits and for delaying closing of the said other relay circuit for a predetermined time after the relay is deenergized.

3. A fuel burner control system comprising in 45 combination with a source of current, an electrically operated relay; two controlling circuits for the relay; a switch in one of said two circuits, and the other of said circuits being closed by the relay; a thermal device for opening the 50 said switch at a predetermined temperature thereof; an electric heater for heating the thermal device, said heater being connected in both of said circuits; and an electrically operated fuel feeding device, said relay being adapted to connect the fuel feeding device and the heater in series circuit relation and with the source of current, the resistance of said one circuit limiting the flow of current to a value insufficient to heat 55 the thermal device to said predetermined temperature, and the current in the fuel feeding device energizing the heater to heat the thermal device above said predetermined temperature.

4. A fuel burner control system comprising in 65 combination with a source of current, an electrically operated relay; two controlling circuits for the relay; a switch in one of said two circuits, and the other of said circuits being closed by the 70 relay; a thermal device for opening the said switch at a predetermined temperature thereof; an electric heater for heating the thermal device, said heater being connected in both of said circuits; an electrically operated fuel feeding device, said relay being adapted to connect the fuel 75

feeding device and the heater in series circuit relation and with the source of current, the resistance of said one circuit limiting the flow of current to a value insufficient to heat the thermal device to said predetermined temperature, and the current in the fuel feeding device energizing the heater to heat the thermal device above

said predetermined temperature; and means actuated by the thermal device for deenergizing the heater when the said thermal device reaches a predetermined temperature above the first predetermined temperature.
